ATTORNEYS

The tubes disclosed are intended for installation in any designed hull, from a small gas boat to the largest battleship, wherein, by the momentum set up in the tubes by the boat moving through the water I provide a means of exhausting the propulsion engines to a vacuum instead of against atmospheric pressure, and thus avoid retarding boat speed, and hence decrease operating and installation costs.

Although I have described a preferred embodiment of my invention in specific terms, it is to be understood that various changes may be made in size, shape, materials and arrangement without departing from the spirit and scope of the invention as claimed.

I claim:

In a boat including a hull, a screw propeller at the stern thereof, and internal combustion means including a pair of exhaust ports, a pair of elongated open tubes arranged in parallel spaced relation with respect to each other and supported longitudinally within said hull, one end of each of said tubes extending through the bow of said hull below the water line to receive water therethrough as the hull is propelled, the other end 25 of each of said tubes being supported within the stern of the boat in aligned relation with said screw propeller to discharge said water against opposite sides of said propeller, the portion of each of said tubes adjacent said other end being 30

5 constricted to create a partial vacuum whereby said internal combustion means may be exhausted into a pressure less than atmosphere, and conduit means having an end connected to each of said exhaust ports and the other end in communication with the restricted portion of each of said tubes.

ROBERT X. MACARTHUR.
